(57) **CLAIM**

The ornamental design of a conveyor rubber based pulley lagging with staggered embedded ceramic segments, as shown and described.

DESCRIPTION

FIG. 1 is a top surface view of a conveyor rubber based pulley lagging with staggered embedded ceramic segments showing my new design;

FIG. 2 is a cross sectional view taken along the line A—A of FIG. 1; and,

FIG. 3 is a cross sectional view taken along the line B—B of FIG. 1.

1 Claim, 2 Drawing Sheets
